UNITED STATES PATENT OFFICE.

JOHN TURNER, OF DORCHESTER, MASSACHUSETTS.

BILLIARD-TABLE.

1,369,992.

Specification of Letters Patent.

Patented Mar. 1, 1921.

Application filed August 28, 1920. Serial No. 406,568.

To all whom it may concern:

Be it known that I, JOHN TURNER, a citizen of the United States, residing at Dorchester, in the county of Suffolk, in the State 5 of Massachusetts, have invented a certain new and useful Improvement in Billiard-Tables, of which the following is a specification, reference being had to the accompanying drawings.

10 The immediate object of this invention is to improve materially the efficiency of billiard tables, particularly the beds of the same, my purpose being to provide in combination with such beds a specially serviceable textile 15 covering in which the working surface of said covering is formed entirely of wool of such texture and nap that the balls may roll freely thereon, said woolen face being closely interwoven with a cotton back of such weave 20 and strength that it (the cotton back) serves to prevent the tearing or wrinkling of the woolen face by the rolling of the balls thereon by reason of contact with a cue tip resulting from miss-plays. In order to fur- 25 ther strengthen the fabric, and particularly to seal said fabric against the sifting of chalk dust therethrough, I rubberize the said back.

For the purpose of explaining my invention clearly, I have provided the annexed drawings, in which the Figure 1 is a perspective view of a billiard table embodying my present improvement and Fig. 2 is a relatively enlarged, transverse, sectional, view 35 of said table, taken on the line 2—2 of said Fig. 1.

Fig. 3 is a further enlarged detail of a portion of the fabric which covers the bed of the table.

40 Referring to these drawings, the letter *a* indicates a billiard table constructed mainly in the usual manner, that is to say, with cushioned side walls *b*, and slate bed *c*.

While special forms of cloths have occa-

sionally been utilized on the slate bed, it has 45 been most common to cover said bed with a firmly woven sheet of cotton and wool fabric which because of its common use, has become known in the trade as "billiard cloth" but such cloths are more or less unsatisfactory as they are easily wrinkled and torn by the cue action of careless players, and they also permit the finely powdered chalk from the cue tips to sift through the cloth and form ridges thereunder which prevents the 50 free rolling of the balls. To overcome such objectionable results and particularly to provide a perfectly smooth and immovable field, throughout the table, for the balls to roll on, I have combined with such tables a 55 cloth of the type herein shown which consists essentially of a rubberized cotton back and woolen top, the construction or weave of the fabric being such that, in the operation of weaving, the wool weft is delivered 60 under light tension and is then beaten up (into the relatively hard cotton warp) so hard that the wool is forced outward and upward thus completely covers and hides the 65 cotton warp, and thus provides a surface 70 for the balls to roll upon which is soft and offers practically no resistance to the rolling of the balls, while the relatively firmer and harder cotton back prevents the wool face of the fabric from stretching or wrinkling. As 75 a result, of such special fabric construction, the balls run absolutely true along every part of the cloth. In the drawings *d* denotes the cotton warp, *e* denotes the woolen filling and *f* the rubber back.

Having thus described my invention, I claim:—

In combination with a table of the class referred to, a bed cloth comprising, in a single structure, a rubberized cotton warp 85 back, and a wool top interwoven with said back and completely inclosing said warp.

JOHN TURNER.
